CLAIM

The ornamental design for an adhesive foot support strap, as shown and described.

DESCRIPTION

FIG. 1 is an obverse side view, taken looking at the front of the adhesive foot support strap.

FIG. 2 is a reverse side view, taken looking at the back of the adhesive foot support strap.

FIG. 3 is a left side view, taken looking at the left side of the adhesive foot support strap.

FIG. 4 is a right side view, taken looking at the right side of the adhesive foot support strap.

FIG. 5 is a top plan view taken looking down at the top of the adhesive foot support strap; and,

FIG. 6 is a bottom plan view taken looking up at the underside of the adhesive foot support strap.

The broken lines in the figures are for the purpose of illustrating portions of an adhesive foot support strap and form no part of the claim.
